CLAIM

The ornamental design for a circular internal lynchpin structure, as shown and described.

DESCRIPTION

FIG. 1 is a front elevation view of a circular internal lynchpin structure, showing my new design;

FIG. 2 is a back elevation view thereof;

FIG. 3 is a left side elevation view thereof;

FIG. 4 is a right side elevation view thereof;

FIG. 5 is a bottom plan view thereof;

FIG. 6 is a top plan view thereof; and,

FIG. 7 is a perspective view thereof.
